PANEL UNIT FOR RADIANT HEATING

Leo A. Byrnie, Torrington, Conn.

Application September 12, 1949, Serial No. 115,195

3 Claims. (Cl. 248—68)

1

This invention relates to radiant heating panel units of the type which are adapted to be embedded in ceilings, walls, or floors, so as to permit the circulation of heated water therethrough and more particularly to a prefabricated unit having a plurality of loops of tubing supported in elongated brackets.

One object of this invention is to provide a flat panel unit of the above nature which is very thin and may be completely concealed in a layer of plaster or cement without requiring that said layer be of excessive thickness.

Another object is to provide a unit of the above nature in which the brackets may be readily adjusted longitudinally of the panel while rigidly maintaining the spacing of the loops of tubing whereby said brackets may be aligned with the joists to which they are secured without "blocking," and the installation thereof will be facilitated.

Another object is to provide a unit of the above nature in which the brackets and the tubing are connected by means of an improved joint structure which has a thickness very little greater than the diameter of the tubing, and which has ample strength to prevent deformation of the unit.

Another object is to provide a unit of the above nature which, due to the high heat conduction afforded thereby, will make possible the use of tubing of a smaller diameter than has heretofore been practical.

A further object is to provide a panel unit of the above nature which will withstand handling during storage and shipment, which will be light in weight, simple in construction, inexpensive to manufacture, easy to install and manipulate, and very efficient and durable in use.

With these and other objects in view, there has been illustrated on the accompanying drawing one form in which the invention may conveniently be embodied in practice.

In the drawing,

Fig. 1 is a perspective view showing one of the improved radiant heating panel units as it would appear when installed in a ceiling, prior to the application of plaster.

Fig. 2 is a side view, on an enlarged scale, of a portion of an installed panel unit, the adjacent structural parts being shown in section.

Fig. 3 is a partial perspective view showing one of the clips and a portion of a bracket in exploded relationship, prior to their assembly for holding a length of tubing.

Fig. 4 is a view similar to Fig. 3, but showing

2

the clip fully assembled with the bracket, and showing the tubing in broken lines.

Fig. 5 is a perspective view showing the assembled parts inverted from the position shown in Fig. 4.

Referring now to the drawing, in which like reference numerals denote corresponding parts throughout the several views, the numeral 10 indicates a panel unit comprising a length of tubing 11 which is looped in zig-zag fashion so as to provide a plurality of substantially equal parallel runs 12 having U-bends 13 at their ends. The tubing 11 terminates in opposite ends 14, 15, which are disposed in alignment with the ends of the straight runs 12 adjacent one edge of the unit 10, whereby said panel unit may be readily connected to any suitable source of circulating heated water by means of supply and return pipes 16, 17.

It will be understood that, if desired, the panel unit 10 may be connected in series with similar adjoining panel units by means of additional pipes or U-bends connected to the ends 14, 15.

In order to hold the tubing runs 12 in parallel relationship, provision is made of a plurality of elongated brackets 18, which are approximately parallel to each other and disposed at right angles to the runs 12. The elongated brackets 18 are preferably constructed of sheet metal of right angular cross section, so that each of said brackets comprises a flat base flange 19 and a depending flange or cleat 20. The side flange 20 is cut at predetermined intervals equal to the spacing of the tubing runs 12, thus providing U-shaped notches 21 which extend for the full depth of said flange 20, and in which the runs 12 are disposed so as to engage against the inner surface of the base flange 19.

In order to retain each of the tubing runs 12 securely in the respective notches 21, provision is made of a plurality of sheet metal clips 22, which, prior to assembly, are of right angular form as shown in Fig. 3.

Each of the clips 22 initially comprises a flat clamping flange 23 and a transverse flange 24 which is provided centrally with a U-shaped notch 25 adapted to receive the tubing 11. Both the notches 21 and the notches 25 are preferably of such a width as to receive the tubing 11 with a snug fit without substantial binding at the sides thereof. At points spaced from opposite sides of the notch 25, the flange 24 is provided with separate slots 26 (Fig. 3) which are adapted to receive a pair of lugs 27 struck outwardly from the material of the side flange 20 of the bracket 18.

In securing the tubing 11 to the bracket 18, the clip 22 will be slid toward said bracket from the position shown in Fig. 3 to the position shown in Fig. 4, thus causing the lugs 27 to enter the slots 26. The lugs 27 will then be bent upwardly as viewed in Fig. 4, securing the clip 22 firmly against the outer face of the side flange 20.

The clamping flange 23 of the clip 22 will also be bent upwardly against the side flange 20 at each side of the tubing 11, as indicated in Fig. 4, to cause the clip 22 to firmly embrace the bracket 18 at both sides of the notch 21. In assembly, the operation of attaching the clips 22 to the bracket 18 may be very readily accomplished inasmuch as both the lugs 27 and the clamping flange 23 may be bent in a single operation by striking them in the same direction with a suitable tool, not shown.

It will be noted, however, that a central portion of the clamping flange 23 will not be bent into engagement with the inner surface of the side flange 20, due to the presence of the tubing 12. The clamping flange 23 thus comprises a curved central cradle portion 28 firmly embracing a portion of the periphery of the tubing 11 and closing the notch 21 so as to reinforce the bracket 18.

To facilitate the installation of the panel unit 10, the base flanges 19 of the brackets 18 are provided with a series of apertures 29 through which nails may be driven into the joists J.

Further, the side flange 20 is provided with a series of large circular apertures 30 into which plaster will flow when applied to the unit in its installed position, thus providing plaster "cleats."

Installation

The improved radiant heating panel unit may be installed in or upon substantially any building wall, floor or ceiling in any manner which is deemed expedient. A preferred mode of installation is illustrated in Fig. 2, which shows the panel unit 10 secured beneath a ceiling joist J by means of a nail N driven into said joist through one of the apertures 29 in the elongated bracket 18.

The unit 10 will preferably be applied beneath the metal lath L, which will have been previously secured to the joist J. It will be understood that the lath L, may, if desired, be alternatively attached below said unit. Inasmuch as the base flange 19 is quite thin, the operation of driving the nail N will compress the lath L sufficiently behind the bracket 18 to bring the upper surface of the tubing 11 into substantially uniform engagement with the lower surface of said lath.

Thus, in applying the plaster P, the required thickness of the plaster layer will be very little more than the diameter of the tubing 11, inasmuch as the only part of the panel 10 which projects below the tubing 11 is the relatively thin cradle portion 28 of the clip 22. It has been found that when the clips 22 are made of .024" sheet brass, said clips will be sufficiently strong, while contributing very little to the total thickness of the unit 10. When the plaster P is applied, it will surround the tubing 11 and will also enter the apertures 30 so as to become firmly interlocked with the unit 10.

In spite of the fact that the total thickness of the joint between the tubing 11 and the elongated bracket 18 is only slightly greater than the diameter of the tubing itself, it has been found that the bridging action of the clip 22 across the notch 21 so reinforces said joint that

there is practically no likelihood of buckling in the unit 10 during shipment or installation, and the brackets 18 are sufficiently rigid to permit them to be installed either at right angles or parallel to the joists J.

It has also been found that when the brackets 18 are assembled with hard copper tubing, the rigidity of the panel unit 10 will be such that the tubing may be of a reduced diameter and the unit will be held flat, thus avoiding the danger that air pockets will develop in the panel after the heating system is put into operation. Also, the use of small diameter tubing will result in a panel which has a minimum overall depth, and which is very light in weight.

If it is found that the brackets 18 are not properly aligned with the joists J when the panel 10 is in its intended position, said brackets 18 may be readily slid longitudinally of the tubing 11 so as to bring them into proper alignment. The frictional engagement of the brackets 18 upon the tubing 11 is sufficient, however, to prevent accidental displacement of said brackets during shipment or handling prior to installation. This construction will also permit the panels to adjust themselves to heat expansion and contraction during use.

One advantage of the improved unit is that it will permit the tubing therein to be disposed very close to the finished plaster surface when installed, whereby maximum heat conduction may be obtained and tubing of small diameter may be employed.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a panel unit for radiant heating, a plurality of elongated spaced brackets each having a side flange provided with a series of notches, a length of tubing comprising a plurality of runs disposed in said notches, and a plurality of U-shaped clips secured to said brackets by lugs struck out from said side flanges adjacent opposite sides of said notches, said clips embracing the edges of the side flanges of said brackets and bridging said notches for retaining the tubing therein and reinforcing said brackets.

2. In a device for supporting a length of tubing, a bracket comprising a base flange and a side flange disposed in angular relationship, said side flange having a notch for receiving said tubing, and a clip of U-shaped cross section embracing the free edge of said side flange and abutting the opposite surfaces thereof in bridging relationship to said notch and secured to said bracket for retaining the tubing therein, wherein said clip comprises an apertured transverse flange disposed flatwise against one surface of said side flange, said side flange having integral lugs engaged through the apertures in said transverse flange for securing said clip to said bracket.

3. In a device for supporting a length of tubing, a bracket comprising a base flange and a side flange disposed in angular relationship, said side

flange having a notch extending for its full depth, and in which the tubing is disposed, a clip embracing the free edge of said side flange at opposite sides of the notch therein and comprising a transverse flange provided with a notch embracing said tubing, means for securing said transverse flange flatwise against the outer surface of said side flange, said clip also comprising a clamping flange engaging the inner surface of said side flange adjacent opposite sides of the notch therein, and having a central cradle portion engaged over an outer surface portion of the tubing in opposition to the base flange of said bracket.
